FLARE BLOCK FOR RAILWAY CROSSINGS
AND THE LIKEArthur R. Schulze, Johnstown, Pa., assignor to
Carnegie-Illinois Steel Corporation, a corpora-
tion of New Jersey

Application September 9, 1948, Serial No. 48,477

4 Claims. (Cl. 246—465)

1

This invention relates to flare blocks used in railroad track crossings of the articulated design and more particularly to a flare block which is automatically adjustable.

In the conventional articulated railroad track crossing assembly, a solid flare block is used between the running rail and the outside arm to maintain a tight connection between the running rail and the main body casting. The flare block is held in position by horizontal bolts which pass through the inner and outer crossing arms, the running rail, and the flare block. The running rail is held snugly in place by pulling up the horizontal bolts tight enough to deflect the crossing arms. In usage, however, the vibrations and shocks occasioned by passing trains cause wear on the surfaces of the crossing arms, the rail web, and the lateral surfaces of the flare block. This surface wear causes the running rail and the flare block to become loose in a relatively short time. When such looseness once develops, additional wear is accelerated.

The solid flare block, above described, is a single piece casting having one straight side which fits the vertical contour of a T-rail and a horizontally tapered face on the opposite side which fits against the outer arm of the main body casting. The wedge effect of the flare block and the pulling up of the horizontal bolts, which pass through moderately loose holes in the flare block, permit only initial tight assembly. Various expedients have been tried in an effort to eliminate the looseness caused by wear, such as inserting shims between the flare block and the adjacent crossing arm, but all such expedients have failed to bring about the desired result.

For safe operating conditions, it is essential that the running rail assembly into the main crossing body casting be maintained continuously tight. Also, in order to reduce wear and consequent maintenance attention, it is desirable that positive means be provided for taking up or eliminating the looseness developed during operation. This provision should preferably be automatic in its action.

It is, accordingly, an object of my invention to provide a flare block, for use in railroad crossings of the articulated design, which is automatically self-tightening, inexpensive to manufacture, and rugged in construction.

This and other objects will become more apparent after referring to the following specification and attached drawings, in which:

Figure 1 is a plan view of a crossing showing the flare block of my invention installed;

2

Figure 2 is an enlarged plan view of one of the two crossing arms shown in Figure 1;

Figure 3 is a vertical section on the line III—III of Figure 2;

5 Figure 4 is a horizontal section on the line IV—IV of Figure 3; and

Figure 5 is a cross section on the line V—V of Figure 3.

Referring more particularly to the drawings, 10 reference numeral 2 indicates one of the four corners of a cast railroad rail crossing of the articulated type having an inner crossing arm extension 4 and an outer crossing arm extension 6. A running rail 8 is fitted adjacent the outer crossing arm extension 6 in the space between the extensions. Slidably fitted between running rail 8 and the inside crossing arm extension 4 is a wedge-shaped flare block 10.

One side 12 of flare block 10 is adjacent to 20 crossing arm extension 4 and is tapered and shaped to fit the inner contour of crossing arm extension 4. The opposite side 14 of the flare block adjacent the running rail 8 is parallel to and shaped to fit the inner contour of the web of rail 8, thus providing a wedge fit.

A cored opening or elongated recess 16 is provided in the top surface of the flare block in which is disposed a cast hollow block 18. The end wall 20 of recess 16 is shaped with a center projection 22 protruding therefrom in the direction of the block 18 providing a shoulder 24. Intermediate block 18 and end wall 20 is disposed a helical compression spring 24 which surrounds projection 22 and bears against the block 18 on one end and against shoulder 24 on the other.

Elongated bolt holes 26 are provided through the sides of flare block 10. The crossing arm extensions 4 and 6, the running rail 8, and the flare block 10 are maintained in side-by-side relationship by means of horizontal bolts 32 and 34. 40 Bolts 32 and 34 pass through the elongated bolt holes 26 to provide a lost motion mounting for the flare block 10. The sides of the block 10 are provided with bolt holes 36. The projection 22 is provided with a bolt hole 38 which corresponds with a matching bolt hole 39 in block 18 through which extends an assembly bolt 40 having a nut 42 threaded on its shaft. Bolt 40 may serve to hold block 18 close to projection 22 so that spring 50 24 is compressed. A longitudinal groove 44 is provided on the top surface of flare block 10 to accommodate the flange of a wheel riding on the running rail 8 and properly guide the same.

In operation, the flare block is assembled in 55 the shop before shipment into the field for in-

stallation. Spring 24 is placed around projection 22 and the block 18 is positioned in the cored opening 16 adjacent the spring. Bolt 40 is then inserted through bolt holes 39 and 38 and nut 42 threaded thereon. Bolt 40 is pulled up so that block 18 lies closely adjacent to projection 22 and spring 24 is compressed between block 18 and inner wall 20, as best shown in Figures 3 and 4. In order to facilitate the insertion of bolt 40, an opening 46 is provided in the wall of block 18 opposite bolt hole 39. The compressed flare block assembly is then delivered to the field for installation. To install in the crossing in the field after the running rail 8 is placed, the compressed flare block 10 is pushed into position between the running rail and the inner crossing arm extension 4 with its bolt holes 26 in alignment with the corresponding bolt hole in the crossing arm extensions and running rail. Bolt 34 is then put in place through the crossing arm extensions 4 and 6, the rail 8, and the flare block 10 in normal manner and the bolt 40 is fully unscrewed with a wrench suitable for that purpose. The spring 24 then acts to push the tapered flare block forward into a snug wedging position. This is accomplished by spring 24 forcing block 18 against the bolt 34 and then using the block as a fulcrum point the spring 24 forces the flare block forward snugly into position between the running rail 8 and outer crossing arm extension 6. The holding bolts 32 are then tightened in the normal manner to fix the running rail and flare block in side-by-side position between the crossing arm extensions. The elongated bolt holes 26 and the end clearance 48, as shown in Figure 3, enable the flare block to be moved longitudinally by the spring to take up any looseness developed in the assembly. Thus, the flare block of my invention functions automatically to take up any looseness in the assembly at the instant it occurs, eliminating the need for manual adjustment during the lifetime of the crossing.

While a crossing of the articulated type is shown and described, the automatic positioning design may be equally well applied to solid cast, insert or built-up types, as well as other track applications.

While one embodiment of my invention has been shown and described it will be apparent that other adaptations and modifications may be made without departing from the scope of the following claims.

I claim:

1. In a railroad rail crossing having two crossing arm extensions with a space therebetween on each crossing arm, and a running rail in said space adjacent one of said crossing arm extensions, the improvement consisting of a flare block having a recess in its top surface disposed intermediate said other crossing arm extension and said running rail, said crossing arm extensions, running rail and flare block being bolted together, a hollow block disposed in the recess of said flare block, said hollow block being adapted to bear against one of said holding bolts, and resilient means in said recess for urging said flare block inwardly between said running rail and said crossing arm extensions.

2. In a railroad rail crossing having two crossing arm extensions with a space therebetween on each crossing arm, and a running rail in said space adjacent one of said crossing arm extensions, the improvement consisting of a flare block having a recess in its top surface disposed intermediate said other crossing arm extension and

said running rail, said crossing arm extensions, running rail and flare block being bolted together, a hollow block disposed in the recess of said flare block, said hollow block being adapted to bear against one of said holding bolts, and resilient means in said recess bearing against said hollow block on one end and against the forward wall of said recess on the other end for urging said flare block inwardly between said running rail and said crossing arm extensions.

3. In a railroad rail crossing having two crossing arm extensions with a space therebetween on each crossing arm, and a running rail in said space, the improvement consisting of a flare block having a recess in its top surface slidably fitted intermediate said running rail and one of said crossing arm extensions, said crossing arm extensions, running rail and flare block being bolted together by means of a plurality of holding bolts extending transversely therethrough, a hollow block disposed in said recess, one of said holding bolts extending transversely through said recess and through said hollow block contained therein, said latter named holding bolt being adapted to provide an abutment for said hollow block, the remainder of said holding bolts extending transversely through elongated bolt holes in said flare block intermediate said recess and the forward end of said flare block to provide a lost motion mounting for said flare block, resilient means in said recess bearing against said hollow block on one end and against the forward wall of said recess on the other end for urging said flare block inwardly between said running rail and said crossing arm extensions.

4. In a railroad rail crossing having two crossing arm extensions with a space therebetween on each crossing arm, and a running rail in said space adjacent one of said crossing arm extensions, the improvement consisting of a flare block having a recess in its top surface slidably fitted intermediate said running rail and said other crossing arm extension, said flare block having a flange groove in its top surface adjacent said running rail, said running rail and said flare block being held together intermediate said crossing arm extensions by means of a plurality of holding bolts extending transversely therethrough, a hollow block disposed in said recess, one of said holding bolts extending transversely through said recess and through said hollow block contained therein, said latter named holding bolt being adapted to provide an abutment for said hollow block, the remainder of said holding bolts extending transversely through elongated bolt holes in said flare block intermediate said recess and the forward end of said flare block to provide a lost motion mounting for said flare block, a helical compression spring disposed in said recess bearing against said hollow block on one end and against the forward wall of said recess on the other end for urging said flare block inwardly between said running rail and said crossing arm extensions.

ARTHUR R. SCHULZE.
